UNITED STATES PATENT OFFICE.

ARTHUR A. MERRITT, OF WORCESTER, MASSACHUSETTS, ASSIGNOR TO WILLCOX & GIBBS SEWING MACHINE CO., OF NEW YORK, N. Y., A CORPORATION OF NEW YORK.

FEED MECHANISM FOR SEWING MACHINES.

Application filed November 22, 1921. Serial No. 517,060.

This invention relates to feeding mechanism for sewing machines and though especially designed for use in what is commercially known as the Willcox & Gibbs Sewing Machine Company's "Feldlock Machine," partly shown for example in Merritt Patent No. 1,253,507 dated Jan. 15, 1918, is applicable to sewing machines generally.

It is common in some types of sewing machines, as illustrated for example in the aforesaid Merritt patent and also in Merritt Patent 1,041,658, dated October 15, 1912, relating to what is commercially known as the Willcox & Gibbs Sewing Machine Company's "Flatlock Machine," to employ feed mechanisms in which the feed-dog or member, is rigidly attached to and projects beyond one end of an approximately horizontal lever which simultaneously reciprocates longitudinally and oscillates vertically on a horizontal fulcrum or axis. In such structures there is considerable of what may be called "overhang" of the feed-dog beyond the fulcrum, that is to say, the feed-dog projects or is located considerably beyond the fulcrum of its lever, as shown by the patents aforesaid. When the feed-dog in such structures is at the limit of its upward movement with the presser-foot resting against the feed-dog or the interposed work, the upper surface of the feed-dog is practically horizontal or parallel with the surface of the cloth-plate through which said dog projects; but as the gripping points or teeth of feed surface or surfaces of said feed-dog begin to rise through their slots in the cloth-plate they are inclined downward in the direction of feed so that the end of the feed surface nearest the operator first engages the work and grips it against the presser-foot, the incline gradually diminishing as the feed-dog rises to the limit of its upward movement. Then in the descending movement of the feed-dog there is a gradual reverse tilting thereof and disengagement of its feed surface with the work, just the reverse of what happens in the upward movement of the feed-dog. In other words, the travel of the feed surface above the cloth-plate is in a curved path bowed upwardly from the surface of the throat-plate so that the teeth of the feed surface progressively engage and disengage the work with the maximum number of teeth simul-

taneously in engagement with the work at 55 the very top of the movement of the feed-dog. Such variation in the extent or area of gripping surface applied to the work tends to an uneven control of the work or fabric in the feeding thereof and to an uneven feeding, particularly when operating upon sleazy, flexible, or soft fabric, such as knit goods.

An object of the present invention is to avoid the aforesaid varying, or increasing 65 and then decreasing, engagement of feed surface with the work and provide feeding mechanism in which the teeth or gripping surface or surfaces of the feed-dog will rise through their slot or slots of the cloth-plate 70 parallel to the surface of said plate and maintain such parallelism throughout their movement above the surface of the cloth-plate, so that a maximum of feed surface will be in engagement with the work 75 throughout each feed movement imparted thereto. Another object is to attain such movement of the feed-dog by driving means which impart movement to said feed-dog at both ends thereof, preferably through pivotal connections to both said ends. Another 80 object is the provision of driving means by which such pivots at both ends of the feed-dog are caused to travel in parallel paths of movement. 85

With the overhang of the feed-dog in prior structures such as hereinbefore mentioned there is some spring or yield of said dog under the downward pressure exerted by the presser-foot and occurring particularly when working upon heavy fabrics, such as overall material, khaki cloth, duck and canvas. Such spring tends to throw the gripping surface of the feed-dog out of proper alignment and detract from the effectiveness of the grip of said surface upon the work to be fed. Another object is to overcome such objectionable spring or yield by firmly supporting the feed-dog at both ends throughout its engagement with the 90 work in feeding the same. 95

Another object is the provision of feeding mechanism of the character indicated capable of operating efficiently at high speed, such for example as required in making three thousand or more stitches per minute. 100

The aforesaid and other objects and ad-

vantages are attained by what is now believed to be the preferred embodiment of the invention illustrated in the accompanying drawings whereof Figs. 3 to 16 inclusive are on practically a full size scale, while Figs. 1 and 2 are on a somewhat reduced scale, and wherein

Fig. 1 is a longitudinal vertical sectional view through the horizontal work supporting part of the work arm of the machine showing the improved feed mechanism and other parts applied thereto;

Fig. 2 is a top plan view of the horizontal work supporting part of the arm of Fig. 1 with its cover removed and showing the feed-dog but omitting other operating parts within the free end of the arm;

Fig. 3 is a vertical section on line 3—3 of Fig. 1, including a showing of part of the work arm extending upward from that illustrated in said Fig. 1;

Figs. 4 and 5 are vertical sections on lines 4—4 and 5—5 respectively of Fig. 1;

Fig. 6 is a plan view of the free end of the horizontal work supporting portion of the work arm, showing particularly the work plate;

Fig. 7 is a side elevation of the end of the work arm shown in Fig. 6 with the slide cover of an opening through the side of the arm removed, the parts within the arm visible through said opening not being shown;

Fig. 8 is a fragmentary front view of the portion of the work arm shown in Fig. 3;

Fig. 9 is a vertical section on line 9—9, of Fig. 8;

Fig. 10 is a detail view of an adjusting gear and rack-plate which latter carries the pivot pin or fulcrum of a vertical lever of the feed driving mechanism;

Fig. 11 comprises detail views of the link which is connected to one end of the feed-dog;

Figs. 12, 13 and 14 are detail views of other parts;

Fig. 15 comprises several detail views of the feed-dog or member and the pivot pins at opposite ends thereof;

Fig. 16 comprises detail views of a link and one of the pivot pins connecting the two horizontal feed levers at one end thereof; and

Fig. 17 is a diagrammatic schematic view showing by the larger full line ellipses or circles paths of travel when the feed mechanism is adjusted to form stitches of maximum length, and showing by smaller dotted line ellipses or circles corresponding paths of travel when the feed mechanism is adjusted to form stitches of minimum length.

In the drawings the operating parts are illustrated in conjunction with a feed-off-the-arm hollow work arm of the type more fully illustrated in Merritt Patent 1,041,352, dated October 15, 1912, said arm including

an upper horizontally extending part 20, a portion only of which is shown in Fig. 3, a vertically depending part 21, Figs. 1, 3, 8 and 9, and a horizontal work supporting part 22, Figs. 1, 2 and 3, having a free end off which the finished work is fed. Three screws 23, only two of which are shown in Fig. 1, extending upward through openings 24, Fig. 2, in the wall of part 22 of the arm, rigidly secure said part to the lower end of the vertically depending part 21 of the arm. In the present machine the part 22 of the arm is made somewhat deeper than the corresponding part in the patents aforesaid to accommodate parts of the feed mechanism of this invention. At the free end of the part 22 of the arm there is a U-shaped cloth-plate frame 25 properly positioned by dowel pins 26, 26 projecting upwardly from the wall of arm 22, Fig. 2, and secured by two screws (not shown) adapted to extend upward through openings 27, 27 in the wall of the work arm and at their upper threaded ends engaged screw threaded openings (not shown) in the underside of the frame 25. Work plate or cloth-plate 28 is applied over frame 25, properly positioned thereon by dowel pins 29, 29 projecting upwardly from the frame and secured in place by three screws 29', Fig. 6. A removable cover 80 for the part 22 of the work arm is beveled at its edge at one end to engage beneath the undercut edge of cloth-plate 28 (Fig. 1) and at its other end is secured in place by a bolt latch 81 having a conical point adapted to seat in a conical depression in the wall of part 21 of the work arm.

Fig. 1 shows a number of operating parts having to do with stitch formation and which are shown in position relative to the improved feed mechanism but which constitutes no direct part of said mechanism or of the present invention, and which are substantially the same as corresponding parts in prior patents. Thus there is a looper lever 30, a looper carrier 31 pivotally mounted thereon by a pivot screw 32 and carrying two loopers 33 one for each of the needles not shown. The looper carrier 31 is held in its normal operative position relative to the looper lever, as shown in Fig. 1, by the latch shown at 34 in said figure and of a construction shown in the prior patents herein mentioned; but said carrier with its loopers may be swung forward in Fig. 1, about pivot 32 and through the opening 35, Fig. 7, in the front wall of the work arm said opening having a slide cover 35', Fig. 5. 36 is a loop spreader having a tail piece 37 pivoting on a screw pivot 38 which engages a supporting bracket arm 39 fastened to and projecting from the inner face of one of the upright walls of the arm. A roller 40 depending from tail piece 37 en-

gages a cam-groove of a part 41, as further shown in Osterhout Patent 1,253,518, Jan. 15, 1918, said part 41 being secured to the looper lever 30, whereby movement of the latter imparts sidewise swinging movement to the loop spreader 36 about its pivot 38. 42 is a loop-check and needle guide supported from one of the side walls of the arm and such as shown in Osterhout Patent 1,134,483, dated April 6, 1915. 43 is a stationary thread take-up member secured to the wall of the arm by a screw 44, and 45 is a movable take-up member secured to looper lever 30, said members operating in a manner more fully set forth in the aforesaid Osterhout Patent 1,253,518. By means not shown, circular movement in a horizontal plane is imparted to the looper lever 30 at its right hand end, Figs. 1 and 2, said end of the lever working between parallel bars or plates 46 and 47. At its other end said lever bears upon a horizontal cross-bar or support 48. 49 is a rotatable fulcrum block in which the looper lever 30 fits and moves longitudinally and which turns with the lever in the compound movement thereof causing the points of the loopers to travel in elliptical paths.

Coming now to the parts constituting the feed mechanism of the present invention 50 is the upper horizontal feed lever fulcrumed to turn and move horizontally upon a pivot pin 51 which is supported at opposite ends in openings through the side walls of part 22 of the work arm. Two bearing blocks 52 embrace the fulcrum pin 51 and are in turn embraced by an elongated capped bearing opening 53 of the lever 50, the cap plate 90 of said bearing being countersunk into a recess on the underside of lever 50, with shoulders 91, 91 at opposite ends of said recess closely fitting the end edges of said plate. Countersunk screws 92, 92 secure plate 90 in place. With considerable upward pressure of the feed-dog, occurring particularly when operating upon heavy work, there is a tendency to bend lever 50 downward at opposite sides of its fulcrum 51 and with a cap plate held in place merely by screws, as shown for example in Figs. 6 and 11 of Merritt Patent 1,041,658, dated Oct. 15, 1912, there is likely to be a yield or give of the lever to the extent of the looseness in fit of the screw threads and bodies of the screws in their holes. This is overcome in the present structure by the cooperation of shoulders 91 with the ends of plate 90.

At its right hand end Fig. 1, lever 50 is pivoted by pin 54 to the lower end of a vertical lever 55 which is fulcrumed to turn and to move longitudinally on the inner reduced end of a pivot screw 56, Fig. 3, the threaded portion of which engages a screw threaded opening through a rack

plate 57, Figs. 3 and 10, and the head of said screw being vertically movable in a countersunk vertical slot 58 in the front wall of the vertical part 21 of the work arm Figs. 3 and 8. The inner end of pivot screw 56 is embraced by two bearing blocks 58' Fig. 1, which are in turn embraced by an elongated capped bearing opening 59 of lever 55. Gear teeth along one vertical edge of rack plate 57 are engaged by a gear wheel 60, Figs. 9 and 10 secured to a short shaft 61 to the outer end of which is fixed a wheel 62, rotatable in a circular opening in a plate 63, Figs. 8 and 9, secured by a screw 64 in an opening through the front wall of the vertical part 21 of the work arm. Screw 64 engages a block 65, Fig. 9, secured within the vertical part of the work arm by screws 66 and 67.

The position of the pivot screw 56 determines the length of feed movement of the feed-dog and hence the length of stitch produced. Normally said screw is turned to position to draw rack plate 57 into tight engagement with the wall of part 21 of the work arm, Fig. 3, thus locking the pivot in the desired position of operation. To adjust the position of the pivot screw and correspondingly change the length of stitch produced, said screw 56 is first turned in reverse direction sufficient to loosen plate 57, and the wheel 62 is then rotated the desired amount, which may be accurately determined by the scale thereon, Fig. 8, correspondingly rotating the gear wheel 60 in engagement with the teeth of the rack plate, raising or lowering said plate and with it the pivot screw 56, the head of the latter moving up or down, as the case may be, in the slot 58. When the parts have been thus adjusted to the desired position, the pivot screw 56 is locked in position by again rotating the same to draw the rack plate into tight engagement with the wall of the work arm.

70 is the feed-dog shown as having a feed-surface consisting of four sections or parallel rows of teeth movable in corresponding slots in the cloth-plate 28. At its front end, that is its right-hand end in Fig. 1, said feed-dog is pivoted by pivot screw 71 to the end of feed lever 50. At its other or rear end said dog is pivoted by pivot screw 72 to the upper end of a vertically disposed link 73 the vertical flat side edges of which make close sliding engagement with the side walls of the work arm (see Fig. 5) to prevent sidewise movement of the link and end of the dog to which it is joined. Pivot screw 74 connects the lower end of link 73 to one end of a feed lever 75, said lever extending along the bottom of part 22 of the work arm and at its other end being joined by pivot screw 76 to the lower end of a link 77 the upper

end of which is connected by pivot screw 78 to the upper feed lever 50. Intermediate of its ends lever 75 is fulcrumed on a horizontal screw pivot pin 79 which spans the space 5 between and is secured in two arms of an inverted U-shaped bearing block 95, the lever 75 passing through said block in the space between the arms thereof. Block 95 has a cylindrical exterior surface fitting 10 rotatably in the curved recesses 96 and 97, Fig. 2, in the inner surfaces of the vertical side walls of the work arm. The hereinbefore mentioned block 49, which has a cylindrical exterior surface, also rotatably fits in 15 said recesses 96 and 97 above and resting upon the block 95, as shown in Figs. 1 and 4. A circular plate 98 fits in said curved recesses above block 49 and over lever 30 and is engaged and secured in place by 20 screws 99, 99 through the side walls of the work arm, said plate thus holding the parts beneath it down to proper position during 25 operation thereof.

In the operation of the feeding mechanism, the vertical lever 55, being simultaneously reciprocated longitudinally and oscillated laterally on its pivot screw or fulcrum 56 by driving connections (partly shown in Fig. 3) such as shown in the aforesaid Merritt Patent 1,041,658, actuates upper feed lever 50 through pivot connection 54 imparting to said lever simultaneous longitudinal reciprocating and lateral oscillating movements on its pivot pin or fulcrum 51. Lever 50, acting through pivotal connection 71, to the forward end of feed-dog 70, imparts to said dog continuous movement in an elliptical or circular path, raising and lowering the feed surface of said dog through the work plate to engage and disengage the work and moving said dog longitudinally while in engagement with the work to feed the same. The lower feed lever 75, actuated at one end through the link connection 77 to lever 50, is thereby oscillated on its fulcrum 79, and acting at its other end through link connection 73 raises and lowers the rear end of the feed-dog while at the same time, because of the freedom of the link 73 to vibrate on its pivot 74, leaving feed-dog 70 unhampered in making its longitudinal feed movements communicated thereto by lever 50 as already described.

Fig. 17 diagrams or plots the driving connections to the feed-dog and differences of movement for different adjustments of the driving connections for the formation of different lengths of stitch. With the pivot pin or fulcrum 56 set to the limit of its upward adjustment, as shown by full lines in Fig. 17, the driving connections of the feed-dog will be actuated on paths of movement shown by the full line circles or ellipses and resulting in stitches of maximum length. With the pivot pin or fulcrum 56 set to the

limit of its downward adjustment, as shown by dotted lines in Fig. 17, the corresponding paths of movement are shown in dotted lines resulting in stitches of minimum length. As shown, each dotted line ellipse 70 and its corresponding full line ellipse have the same length of vertical axis, representing up and down movement of the feed-dog. But said ellipse differ as to length of horizontal axis representing forward and backward movement, that part of such movement which is above the surface of the cloth-plate representing and determining the length of each forward feed movement imparted to the work and hence the length of 80 stitch produced. It will also be seen that the vertical movement at both ends of the feed-dog is the same for any given adjustment, so that in all positions of movement, and whatever the adjustment as to length of 85 stitch, the vertical movement of the feed-dog surface of the dog is always the same and will at all stages of its engagement with the work stand parallel to the surface of the cloth-plate. 90

What I claim is:

1. In a sewing machine, the combination of a feed-member for engaging and feeding the work, and driving means therefor including two relatively movable members connected respectively to opposite ends of said feed-member said driving means being arranged and adapted to positively impart like upward and downward and forward and backward movements to both ends of 100 said feed member.

2. In a sewing machine, the combination of a feed-member for engaging and feeding the work, and driving means therefor including two members pivotally connected 105 respectively to opposite ends of said feed-member said driving means being arranged and adapted to impart to the feed member through said two members like upward and downward and forward and backward movements to both ends of said feed member.

3. In a sewing machine, the combination of a cloth-plate, a feed-member having a feed-surface adapted to operate through and above said cloth-plate, and driving 115 means including two relatively movable members connected respectively to opposite ends of said feed-member said driving means being arranged and adapted to impart to the feed member through said two members 120 like upward and downward and forward and backward movements to both ends of said feed-member as to that part of its travel during which its feed-surface is above the cloth-plate.

4. In a sewing machine, the combination of a cloth-plate, a feed-member having a feed-surface adapted to operate through and above said cloth-plate, and driving means including two members pivotally con- 130

nected respectively to opposite ends of said feed-member said driving means being arranged and adapted to impart to the feed member through said two members like 5 upward and downward and forward and backward movements to both ends of said feed-member as to that part of its travel during which its feed-surface is above the cloth-plate.

10 5. In a sewing machine, the combination
of a cloth-plate, a feed-member having a
feed-surface adapted to operate through
and above said cloth-plate, and driving
means including two relatively movable
15 members connected respectively to opposite
ends of said feed-member said driving
means being arranged and adapted to im-
part to the feed member through said two
members like upward and downward and
20 forward and backward movements to both
ends of said feed-member during the work-
feeding part of its travel.

6. In a sewing machine, the combination
of a cloth-plate, a feed-member having a
feed-surface adapted to operate through
and above said cloth-plate, and driving
means including two levers pivotally con-
nected respectively to opposite ends of said
feed-member said driving means being ar-
ranged and adapted to positively impart
like upward and downward and forward
and backward movements to both ends of
said feed-member as to that part of its
travel during which its feed surface is
above the cloth-plate.

40 7. In a sewing machine, the combination of a feed-member for engaging and feed-
ing the work, and driving means therefor including two levers pivotally connected
45 respectively to opposite ends of said feed-
member said driving means being adapted and arranged to impart to said feed mem-
ber through said two levers like upward and downward and forward and backward
movements to both ends of said feed-mem-
ber during the work-feeding part of its travel.

50 8. In a sewing machine, the combination
of a work arm having an approximately
horizontal free ended work supporting
part, a feed-member, and driving means for
said feed-member including two members
extending along said work supporting part
of the arm and connected respectively to
opposite ends of the feed-member said driv-
ing means being arranged and adapted to
impart like movement to both ends of said
feed-member.

60 9. In a sewing machine, the combination
of a cloth-plate, a feed-member having a
feed-surface adapted to operate through
and above said cloth-plate, and driving
means including two levers pivotally con-
nected respectively to opposite ends of said
65 feed-member said driving means being ar-

ranged and adapted to impart to said feed member through said two levers like upward and downward and forward and backward movements to both ends of said feed-member as to that part of its travel during which its feed-surface is above the cloth-plate. 70

10. In a sewing machine, the combination of a work arm having an approximately horizontal free ended work supporting part, a cloth-plate mounted on said arm at or near the free end thereof, a feed-member having a feed-surface adapted to operate through and above said cloth-plate, and driving means including two levers pivotally connected respectively to opposite ends of said feed-member said driving means being arranged and adapted to impart to said feed member through said two levers like upward and downward and forward and backward movements to both ends of said feed-member as to that part of its travel during which its feed-surface is above the cloth-plate. 75 80 85

11. In a sewing machine, the combination of a work arm having an approximately horizontal free ended work supporting part, a feed-member at or near the free end of said arm, and driving means for said feed-member including an upper and a lower feed-lever extending along said work supporting part of the arm and connected respectively to opposite ends of the feed-member. 95

12. In a sewing machine, the combination of a work arm having an approximately horizontal free ended work supporting part, a feed-member at or near the free end of said arm, and driving means for said feed-member including an upper and a lower feed-lever extending along said work supporting part of the arm the upper feed-lever being pivotally connected directly to one end of the feed-member and the lower feed-lever being pivotally connected to the other end of the feed-member through the intermediary of a link-member. 100 105 110

13. In a sewing machine, the combination of a work arm having an approximately horizontal free ended work supporting part, 115 a cloth-plate mounted on said arm at or near the free end thereof, a feed-member having a feed-surface adapted to operate through and above the surface of said cloth-plate, and driving means for said feed-member including an upper and a lower feed-lever extending along said work supporting part of the arm and connected respectively to opposite ends of the feed-member said driving means being arranged and adapted to impart like movement to both ends of said feed-member as to that part of its travel during which its feed-surface is above the cloth-plate. 120 125

14. In a sewing machine, the combination 130

of a work arm having an approximately horizontally free ended work supporting part, a cloth-plate mounted on said arm at or near the free end thereof, a feed-member 5 having a feed-surface adapted to operate through and above the surface of said cloth-plate, and driving means for said feed-member including an upper and a lower feed-lever extending along said work supporting 10 part of the arm the upper feed-lever being pivotally connected directly to one end of the feed-member and the lower feed-lever being pivotally connected to the other end of the feed-member through the intermediary 15 of a link-member and said driving means being arranged and adapted to impart like movement to both ends of said feed-member as to that part of its travel during which its feed-surface is above the 20 cloth-plate.

15. In a sewing machine, the combination of a work arm having an approximately horizontal free ended work supporting part, feed driving means including an upper and 25 a lower feed-lever both extending along said work supporting part of the arm, and a feed-member located at or near the free end of said arm said feed-member being at one end pivotally connected to and supported from 30 the end of one of said feed-levers and at its other end being pivotally connected and supported from the end of the other of said feed-levers.

16. In a sewing machine, the combination 35 of a work arm having an approximately horizontal free ended work supporting part, feed driving means including an upper and a lower feed-lever both extending along said work supporting part of the arm, and a feed-member located at or near the free end of said arm said feed-member being at one end pivotally connected directly to and supported from the end of the upper feed-lever and at its other end being pivotally connected to and supported from the end of the lower feed-lever through the intermediary 45 of a link.

17. In a sewing machine, the combination 50 of a feed-member for engaging and feeding the work, and driving means therefor including two relatively movable members connected respectively to opposite ends of said feed-member and by which the latter is supported and actuated, like movement imparted to both ends thereof during that part of its travel in which it is feeding the work.

18. In a sewing machine, the combination 55 of a feed-member for engaging and feeding the work, and driving means therefor including two relatively movable members connected respectively to opposite ends of said feed-member and by which the latter is both supported and actuated said driving means

being arranged and adapted to impart to said feed member through said two members 65 like upward and downward and forward and backward movements to both ends of said feed-member during that part of its travel in which it is feeding the work.

19. In a sewing machine, the combination 70 of a feed-member operating in an approximately horizontal position, and driving means therefor including approximately horizontal upper and lower feed-levers, said feed-member being pivotally connected to 75 and supported at one end from the upper feed-lever and pivotally connected to and supported at its other end from the lower feed-lever.

20. In a sewing machine, the combination 80 of a feed-member for engaging and feeding the work, and driving means including two levers pivotally connected respectively to opposite ends of said feed-member and through which pivotal connections said 85 feed-member is supported by said levers and also actuated by said levers to impart to said feed member four-motion feed movements.

21. In a sewing machine, driving connections including a lever having an opening 90 in one side thereof, a bearing positioned in said opening and constituting a fulcrum for said lever, the work imposed upon said lever in operation tending to bend the same in a manner to contract said opening in the side 95 of the lever, and a cap plate secured to said lever and spanning said opening at the open side thereof said plate closely fitting between two shoulders on the lever opposed to the end edges respectively of the plate and thus resisting contraction of the opening 100 by the work imposed on the lever.

22. In a sewing machine, the combination 105 of a feed-member operating in an approximately horizontal position, two approximately horizontal and approximately parallel feed-levers one connected to and supporting said feed member at one end thereof and the other feed-lever connected to and supporting said feed-member at its other end, and means actuating said feed levers to impart feed movement to said feed-member.

23. In a sewing machine, the combination 115 of a feed-member operating in an approximately horizontal position, two approximately horizontal and approximately parallel feed-levers connected at corresponding ends to opposite ends respectively of said feed-member and thereby also supporting said feed-member at both ends, and means actuating said feed-levers to impart feed movements to said feed-member.

In testimony whereof I have signed this specification.

ARTHUR A. MERRITT.
